UNITED STATES PATENT OFFICE.

EDWARD B. MANNING, OF MIDDLETOWN, CONNECTICUT.

DESIGN FOR TEA AND COFFEE POT BASE.

Specification forming part of Design No. 6,898, dated September 30, 1873; application filed July 17, 1872.
[Term of Patent 7 years.]

To all whom it may concern:

Be it known that I, EDWARD B. MANNING, of Middletown, in the county of Middlesex and State of Connecticut, have invented a new Design for Tea and Coffee Pot; and I do hereby declare the following, when taken in connection with the accompanying drawings and the letters of reference marked thereon, to be a full, clear, and exact description of the same, and which said drawings constitute part of this specification, and represent, in—

Figure 1, a side view of a pot, with the bottom attached; Fig. 2, a transverse section on line $x\ x$; and in Fig. 3, a perspective view.

This invention relates to a design for that class of tea and coffee pots in which the base or lower portion is formed from hard metal, as in the patent granted to me June 3, 1862; re-issued June 27, 1865; again reissued September 26, 1865; and the design consists in the peculiar form of the said lower portion of the pot.

At the intersection of the upper portion A and lower portion B—that is, the line $x\ x$ —the form of the pot is that of an el-

lipse, as seen in transverse section, Fig. 2, and at this point a bead, a , forms or covers the joint between the two. This bead is made by the manufacturer in the process of uniting the bottom with the upper portion. The article is complete without the bead, and from the upper edge the bottom is contracted downward, the design being for the elliptical shape and bead a .

It will be understood that this bottom for the pot is an article of commerce complete in itself, and is in this form furnished to manufacturers, who attach the bottoms to tops of their own manufacture.

I claim as my invention—

The design for bottom of tea and coffee pots, of an elliptical form in transverse section, contracted downward from the upper edge to the bottom, as shown in the accompanying drawings, and as herein described.

EDWARD B. MANNING.
